UNITED STATES PATENT OFFICE.

ERNEST J. HENRY, OF CEDAR RAPIDS, IOWA.

AUTOMATIC FURNACE-DAMPER CONTROLLER.

1,395,709.

Specification of Letters Patent. Patented Nov. 1, 1921.

Application filed April 21, 1919. Serial No. 291,495.

To all whom it may concern:

Be it known that I, ERNEST J. HENRY, a citizen of the United States, residing at Cedar Rapids, in the county of Linn and State of Iowa, have invented certain new and useful Improvements in Automatic Furnace-Damper Controllers; and I do hereby declare the following to be a full, clear, and exact description of the invention, such as will enable others skilled in the art to which it appertains to make and use the same.

This invention relates to the regulation of the action of furnaces, the object of the invention being to provide means whereby the active draft of the furnace may be automatically started at a predetermined time, after having been checked, as for keeping a low fire over night. The invention involves also means for automatically checking the draft again, should the restored draft result in excessive heating of the furnace.

The nature of the invention is fully disclosed in the description and claims following, reference being had to the accompanying drawing, in which:—

Figure 1 is a side elevation of apparatus embodying my invention as applied to a furnace, the positions of parts indicating a low fire with drafts checked. Fig. 2 is a side elevation of the controlling mechanism, with one side of the inclosure removed, and certain parts in section. Fig. 3 is a plan view of the same, with the position of the clock reversed.

In the drawing, the numeral 1 denotes a furnace, having a fire door 2 with a lifting check-damper 3, and an ash-door 4 with its lifting draft-damper 5. From the furnace extends a smoke-pipe 6, provided with a check-damper 7. These may all be of the usual construction, and need no description. The line 8 indicates the bottom edge of a floor-joist, to one or more of which may be attached a series of pulleys for various chains, as will appear in the description following.

Connecting with the draft damper 5 is a chain 9 running directly to the room above, for convenience in regulating the furnace from upstairs. A second chain 10, in connection with pulleys 11 and 12, connects with the check-damper 7. These are also of familiar construction and operation. As shown in Fig. 1 these chains may have been

adjusted in the room above the furnace, and are in position to retard the furnace draft, and induce low combustion, as is commonly desired for night service. The effect of this is to so reduce the temperature in the house as to make it uncomfortable to rise and dress in, unless the normal draft of the furnace has been previously restored. Means for accomplishing this object automatically, and while the householder may be asleep, will now be described.

Referring now more particularly to Figs. 2 and 3, the numeral 13 denotes a stand having opposing vertical walls 14. In or closely adjacent to openings in these walls is set an alarm clock 15 having a T-headed vibrator 16. The clock is best held in position by an encircling band 17 attached at one end to the end of the stand, and at the other end provided with a screw-threaded stem 18 passing through a hole in the band, and through the end of the stand, where it is secured by a nut 19. The clock may thus be conveniently shifted from one side to the other of the case, according to its location with respect to the furnace, or light, or otherwise. Pivoted in the case at 20 is a trip-lever 21, whose blade 22 is notched at 23 and 24, so as to engage the vibrator whichever side of the case the clock may be set. A cross-rod 25 serves as a stop for this lever when tripped. At the other end of the stand is pivoted at 26 a long lever 27, whose inner end may overlap the short arm of the trip-lever, as shown. A weight 28 serves to depress the long lever when the other is tripped. This weight is preferably mounted to slide along the longer lever, and is fastened at any desired point by a thumb-screw 29. The lever is also provided with a series of similarly mounted slide-hooks, 30, 31 and 32, to engage various pull-chains. The hook 30, on the inner side of the pivot, connects with a chain 33, which passes over pulleys 34 and 35, its free end having a hook 36 to engage the damper-chain 9. When so connected, it will be evident that the release of the long lever will, by its tilting action, pull the damper-chain, and so open the damper 5. At the other side of the lever's pivot a hook 31 connects by a chain 37 with the check-damper chain 10, the action of this chain being of course contrary to that of the damper-chain. Provision is also made for similarly operating

the fire-door check-damper, by means of a chain 38 running over pulleys 39 and 40, and connecting with the hook 32. The depression of the long lever is regulated by 5 a rod 41 and a series of holes 42 in the stand, the drop of the lever varying the lift of the draft-damper, as will be evident. In the case of slow-burning fuel the connection with the fire-door check may be dispensed 10 with, but it is useful when a free-burning fuel, such as soft coal, is employed.

Assuming the alarm clock to be set, as indicated, when the hour of 5 is reached, the alarm vibrator will be set in motion. This 15 instantly releases the trip-lever, which permits the long lever to drop, and by preponderating weight, lift the draft damper and close the check dampers. This starts the fire into active combustion, and by the 20 time the householder is ready to rise and dress, the house is warm.

It will sometimes happen that the action of the furnace will be too vigorous, and if not controlled, may overheat to a dangerous 25 extent. To guard against this contingency provision is made for reversing the action of the lever and its connected chains. Near the outer end of the lever, to the slide 43, is connected a hanger 44, carrying a weight 45 in 30 excess by weight or leverage, of the inner weight already described. This weight is normally suspended from some part of the furnace subject to overheating, preferably the smoke pipe, by a medium which will be 35 severed by such overheating. This in practice is simply a tow or cotton string 46. When so suspended the levers are free to act as though there were no outer weight at all. When, however, the apparatus shall have 40 tripped, and the furnace has overheated the smoke-pipe, a burned off string will allow the weight 45 to drop to the position shown in Fig. 2, thus again closing the draft damper and checking the fire.

45 In adjusting the apparatus for the night, the operator has only to wind the clock, a little winding of the alarm side being sufficient for tripping purposes, and hook the chain 33 to the damper-chain 9. He then 50 lifts the inner end of the long lever, and rests it on top of the trip-lever, whose blade is made to engage the alarm-clock vibrator. To facilitate the engagement of the levers their ends are beveled to an edge at 47, so 55 that they will easily pass each other, on the uplifting of the long lever.

It will be evident that the construction is such that while the long lever is sufficiently weighted to operate the dampers its inner 60 end rests so near the pivot of the trip-lever that very little strain, and very slight friction is brought to bear on the clock vibrator, and the action of the same is free and unobstructed.

65 It will be noted that the hanger for the

outer weight is of such a length that the weight rests on the floor, when in depending position. To prevent excessive movement of the long lever, furthermore, a cross-rod 48 is placed above it, as shown.

70 The top of the stand is left open for convenience in manipulating the long lever, but to protect the clock from dust a covering cloth 49 is attached at one end, as shown in Fig. 2.

75 In the operation of the furnace during the day the apparatus is left in its disengaged position, which allows the check-dampers to close. The draft-damper chain 33 is unhooked from the chain 9, thus permitting the latter to be manipulated from up-stairs.

Having thus described my invention, I claim:

1. Furnace draft-controlling apparatus, comprising a lever weighted at one side of its pivot, a chain on the weighted side connecting with the draft-damper, a chain on the opposite side connecting with the check-damper, a trip-lever to support the weighted lever, an alarm-clock whose vibrator engages 85 said trip-lever, a preponderating weight connected with said weighted lever, and opposite said weight, and means breakable by the excess heat of the furnace to support said preponderating weight therefrom.

90 2. In apparatus for automatically controlling the draft of a furnace, a weighted lever having a pulling connection on its weighted side with the draft-damper and on the opposite side with the check-damper, a time-controlled connection therewith, a preponderating weight attached to the lever arm opposite the above named weight, and a support for the preponderating weight attachable to some part of the furnace, and 95 breakable by its excess heat.

3. Apparatus for automatically starting the draft of furnaces, and for reversing its action when overheating, the same comprising a time-operated weighted lever adapted 110 to open the draft-damper and close the check-damper at a predetermined time, a counter-weight of greater gravity connected with the lever opposite the forementioned weight, and a burnable cord suspending said 115 counterweight from the smoke-pipe of the furnace.

4. In a furnace draft-controlling device, a supporting stand, a main operating lever pivoted thereto, a weight attached to one 120 arm of the lever, a trip-lever having a short arm to support the weighted arm of the main lever and a plural-notched longer arm to engage an alarm-clock vibrator, an alarm-clock, and means for securing said clock at 125 either side of the stand, and at substantially equal distances from said plural-notched lever.

5. In furnace draft-controlling apparatus, a supporting stand, a main operating lever 130

pivoted thereto, having a draft-controlling weight on one of its arms, and a time-controlled trip-lever to support the weighted end of the main lever, the engaging ends of 5 the levers being edged on their opposite, non-supporting sides, and the main lever having a limited sidewise movement, whereby the levers may easily pass each other at

either side when moved to engaging position. 10

In testimony whereof I affix my signature in presence of two witnesses.

ERNEST J. HENRY.
